(57) **CLAIM**

The ornamental design for a rotating wireless battery charging device, substantially as shown and described.

DESCRIPTION

FIG. 1 is a top perspective view of a rotating wireless battery charging device, shown in a first orientation, according to a first embodiment of the present invention;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a back view thereof;

FIG. 8 is a front view thereof;

FIG. 9 is a top perspective view of the rotating wireless battery charging device of FIG. 1, shown in a second orientation;

FIG. 10 is a right side view thereof;

FIG. 11 is a left side view thereof;

FIG. 12 is a back view thereof;

FIG. 13 is a front view thereof;

FIG. 14 is a top perspective view of a rotating wireless battery charging device, shown in a first orientation, according to a second embodiment of the present invention;

FIG. 15 is a bottom perspective view thereof;

FIG. 16 is a top view thereof;

FIG. 17 is a bottom view thereof;

FIG. 18 is a left side view thereof;

FIG. 19 is a right side view thereof;

FIG. 20 is a back view thereof;

FIG. 21 is a front view thereof;

FIG. 22 is a top perspective view of the rotating wireless battery charging device of FIG. 14, shown in a second orientation;

FIG. 23 is a right side view thereof;

FIG. 24 is a left side view thereof;

FIG. 25 is a back view thereof; and,

FIG. 26 is a front view thereof.

The broken lines in the drawings are for the purpose of illustrating portions of the article that form no part of the claimed design.
